UNITED STATES PATENT OFFICE.

ALBERT C. KONG AND WAH CHONG KAM, OF HONOLULU, TERRITORY OF HAWAII.

QUICK-SERVICE ATTACHMENT-PLUG.

1,304,491.

Specification of Letters Patent. Patented May 20, 1919.

Application filed November 26, 1918. Serial No. 264,256.

To all whom it may concern:

Be it known that we, ALBERT C. KONG and WAH CHONG KAM, citizens of the United States, residing at Honolulu, in the Territory of Hawaii, have invented new and useful Improvements in Quick-Service Attachment-Plugs, of which the following is a specification.

This invention is an improved separable quick service attachment plug, adapted to be snapped rectilinearly into any ordinary Edison or other threaded socket and without the necessity of screwing the plug into the socket and without liability of twisting the conducting cord or cable, the object of the invention being to provide an improved attachment plug of this kind which is simple in construction and which can be instantly attached or detached from any ordinary socket such as an Edison socket.

With the above and other objects in view, the invention consists in the construction, combination and arrangement of devices hereinafter described and claimed.

In the accompanying drawings:

Figure 1 is an elevation of a quick service attachment plug constructed and arranged in accordance with my invention.

Fig. 2 is a central sectional view of the same in place in an ordinary Edison socket.

Figs. 3, 4, and 5 are detail views.

Our improved attachment plug comprises a pair of separable members 1, 2. The member 1 has a cylindrical plug portion 3 and is made of fiber or of other suitable insulating material. A band 4, of brass, copper, or other suitable conducting material, is secured around the plug portion 3 and constitutes an electric terminal and is adapted to be spaced in an ordinary electric socket, such as an Edison socket and is of slightly less diameter than the interior diameter of the socket. The conducting band is provided at suitable points with openings 5 and the member 1 has radial recesses 6 which are coincident with said openings. Balls 7, of copper, brass or other suitable conducting material and which are of somewhat greater diameter than said openings, are seated in said openings and movable into said recesses and are normally held in seated, projected position by springs 8 which are arranged in said recesses.

The member 1 has longitudinal openings 9, 10 extending therethrough and is pro-

vided with conducting strips 11, 12 of copper, brass, or other suitable material, and which are arranged and secured, respectively, in said openings, the strip 11 being connected at its outer end with the terminal 60 band 4, as at 13, by being soldered or otherwise suitably secured to said band. The strip 12 has its outer portion bent at right angles, as at 14, and extending inwardly therefrom and secured in the bottom of a 65 recess 15 in the outer end of the member 1 by means of a contact screw 16.

The member 2 is detachably secured to the member 1 by screws 17 and has a central opening through which a conducting cord 70 18 leads. Said member 2 also has a circular recess 19 in its inner side and in the said recess are terminals 20, 21 to which the inner ends of the conducting cord are secured by screws 22, the said terminals being, respectively, provided with contact strips 23, 24 which project from the inner side of the member 2 and are adapted to enter the openings 9, 10 of the member 1 and to, respectively, effect contact with the strips 11, 12, 80 as shown in Fig. 2.

Our improved attachment plug can be instantly arranged in a socket as it is only necessary to insert the band 4 rectilinearly in the socket, no screwing being necessary, 85 the spring projected balls 7 sliding across the internal threads of the socket and engaging one of the threads by the action of the springs 8 when the band is entirely in the socket, the balls and springs coacting with 90 the internal thread of the socket to securely hold the plug in place.

The plug can be instantly withdrawn endwise from the socket as the springs yield and permit the balls to correspondingly 95 yield and release the plug on the application of a moderate degree of force on the plug.

While we have herein shown and described a preferred embodiment of our invention, we would have it understood that changes 100 may be made in the form, proportion and construction of the several parts without departing from the spirit of our invention and within the scope of the appended claims.

Having thus described our invention, we 105 claim:

1. An attachment plug comprising insulating members connected together, one of said members having a passage for wires and the other member having longitudinal 110

openings therethrough and also having a radial recess, a contact band surrounding the second-named member and having an aperture coincident with said recess, a 5 spring-backed element disposed in said recess and aperture and projecting beyond the band, terminals connected to the inner end of the first-named member for the connection of wires and having contact strips disposed 10 in the longitudinal openings of the second-named member, a contact strip arranged in one of the said longitudinal openings in lapped relation to one of the first-named strips and having an end portion 15 abutting against the end of the second-named member and electrically connected with the band, a contact strip arranged in the other of the longitudinal openings in lapped relation to the other of the first-named strips and having an angularly-disposed portion opposed to the end of the second-named member, and contact means connecting said portion and said member.

2. An attachment plug of the class described, comprising a pair of members detachably secured together, one of said mem- 25

bers having a plug portion, a non-threaded contact band therearound, said band having openings and said member having radial recesses coincident with said openings, and 30 said member being further provided with longitudinal openings extending therethrough, contact strips in said openings, one of said strips being connected to said band, a contact screw securing the outer end of 35 the other strip to the outer end of the plug, balls seated in said openings of the band and movable into said radial recesses, and springs in said recesses and normally projecting said balls; the other member having 40 a central opening for the reception of conducting cords and being provided with a recess in its inner side, and terminals secured in said recess and provided with contact strips for arrangement in the longitudinal 45 openings of the plug member and engagement with the strips of the plug member.

In testimony whereof we affix our signatures.

ALBERT C. KONG.
WAH CHONG KAM.
